(57) **CLAIM**

The ornamental design for a dual pod, substantially as shown and described.

DESCRIPTION

FIG. 1 is a top-front-right isometric view of a dual pod;

FIG. 2 is a front view thereof;

FIG. 3 is a side view thereof;

FIG. 4 is a top view thereof;

FIG. 5 is a bottom view thereof;

FIG. 6 is a bottom-rear-left view thereof.

The broken lines in the drawings depict the portions of the dual pod for a vaporizer that form no part of the claimed design.
